UNITED STATES PATENT OFFICE.

JOSEPH SNOWDEN BELL, OF BROOKLYN, NEW YORK.

STEAM-ENGINE.

1,325,186.

Specification of Letters Patent. Patented Dec. 16, 1919.

Application filed April 2, 1918. Serial No. 226,280.

To all whom it may concern:

Be it known that I, JOSEPH SNOWDEN BELL, of Brooklyn, in the county of Kings and State of New York, office No. 149 Broadway, New York, have invented a certain new and useful Improvement in Steam-Engines, of which improvement the following is a specification.

My invention relates generally to reciprocating piston steam engines of the single expansion type, and, more particularly, to marine engines, and its object is to provide an engine of such type which shall be of comparatively simple and inexpensive construction; involve low maintenance charges, effect an economical utilization of steam; and be readily and quickly operable by the engineer, in stopping, starting, and reversing.

The improvement claimed is hereinafter fully set forth.

The material economy, as to fuel and water consumption of multiple expansion steam engines, has long since been fully recognized, and the adoption of this type in engines of large power, particularly those of steam vessels, has, for this reason, become practically universal. So far, indeed, has the general approval been extended, that, in many cases, the important question of commercial economy has been given but little, if any, consideration, and practice which is, theoretically, entirely correct, has been followed, not only without effecting any commercially economical result, but, on the other hand, involving a positive increase of operative cost. This is particularly noticeable in the case of the smaller class of steam vessels employed in harbor, inland, and canal navigation, the engines of which are of comparatively small power, the consumption of fuel not great, and which are often subjected to rough or careless handling. For example, a compound engine has been applied by designers considered to be good authority, in an eighteen foot whale boat, and in forty foot launches, whose maximum consumption of fuel would necessarily be small. Structurally, a compound engine of the fore and aft type, which is that most generally built, is substantially the equivalent of two single cylinder engines, and a triple expansion engine of three, and, in some cases, of four. The latter type also requires an increase of engine room force. Manifestly this increase of machinery and cost is un-

economical, unless substantial reason for it can be adduced, which, except for engines of comparatively large power, does not appear. With small fuel consumption, there is, obviously, not the capacity of effecting any substantial saving in fuel, and whatever small economy of fuel may be attained by the employment of a multiple expansion engine, may be, and generally is, more than offset by the greater overhead charges of interest on cost of construction, and maintenance costs over those of the simpler and less expensive single expansion engine.

The single cylinder engines of the latter type have heretofore been ordinarily operated at comparatively low steam pressures, and have not been fitted with expansion valve mechanism of approved modern type. As a result, their performance has not compared as favorably with that of multiple expansion engines as would be the case under more nearly equal conditions. In many of the older single cylinder engines, the main distribution valve is of the slide type, and expansion is effected by the so-called "Meyer" cut off valves, which are, in fact, those of the U. S. patent of Horatio Allen, No. 2,227, dated August 21, 1841. These cut off valves are blocks, riding on the main valve, and manually adjustable toward and from each other, to close steam passages through the main valve, at earlier or later periods in the stroke. In engines of above, say, twenty-four inches diameter of cylinder, the main valve becomes so heavy that a pinion and segment gear, the operation of which is less speedy and convenient than that of a reverse lever, is required for reversing, and the manual adjustment of the cut off valve blocks, by a ratchet arm, requires additional time. The resultant comparative slowness of reversing, and the liability to put the engine "on the center" in the operation, are materially objectionable in single cylinder engines of the construction above referred to. This objection is minimized, and improved means for effecting and varying cut off are provided, by my invention, without involving any increased cost or complication of the engine structure.

In the accompanying drawings: Figure 1 is a front view, in elevation, of a marine steam engine, illustrating an embodiment of my invention; Fig. 2, a side view, partly in section, of the same, and; Fig. 3 a hori-

zontal section, on an enlarged scale, on the line III, III, Fig. 2.

My invention is herein exemplified as applied in a single cylinder vertical direct acting marine engine, which, except as to the features of my invention hereinafter described, is of a construction long and well known in the art. The cylinder, 1, is bolted to the top of an A frame or pair of housings, 2, which are firmly secured to a bed plate, 3, adapted to be supported on suitable keelsons in a vessel. The cylinder is fitted with a properly packed piston, 4, which is secured on a piston rod, 4^a, passing through a stuffing box, 1^a, in the lower head of the cylinder, and carrying a cross head, 5, which slides on guides, 6, on the housings. The cross head is coupled, by a connecting rod, 7, to a crank pin, fixed in cranks, 8, on a crank shaft, 9, which is coupled to a tail shaft or propeller shaft (not shown) in the usual manner.

In the practice of my invention, referring descriptively to the specific embodiment thereof which is herein exemplified, I provide a valve chest, 10, which is located at the front of the cylinder, 1, and is preferably, as shown, cast integral therewith. The valve chest is closed at its ends by removable heads, 10^a, and communicates, near its ends, with induction and eduction ports, 1^b, 1^c, formed in the cylinder casting and leading into the cylinder, 1, at opposite ends thereof. A steam passage, 1^d, is formed on the valve chest, intermediate of the ports, 1^b, 1^c, and a steam supply pipe, 12, which is controlled by a throttle valve (not shown), leads from a steam boiler into said passage. An exhaust passage, 10^b, formed on the side of the valve chest opposite the steam passage, opens into the valve chest, at opposite ends thereof, and an exhaust pipe, 13, leads from the exhaust passage to a condenser, or to the atmosphere if the engine be non-condensing.

The main steam distribution valve and the cut-off valve which have been selected for exemplification herein, conform, in all essential particulars, with those which have long been in extended practical service in the well known "Buckeye" stationary steam engine. The latest design of said valves is set forth in Patent No. 808,814, granted to Buckeye Engine Company, as assignee of E. T. Cope, December 19, 1905, and therefore, in and of themselves, they are not claimed as of my invention. They will not, therefore, be more fully described herein than will suffice to make clear their operative relation to the other members with which they are combined.

The main steam distribution valve, comprises two properly packed piston heads, 14, which are connected by rods, 14^a, fitted to be reciprocated in bushings, 11, fitted in the valve chest and to control communication,

through ports, 11^a, therein, and ports, 14^b, in the walls of the piston heads, between the steam passage, 1^d, and the interior of the valve chest, which is continuously open thereto, and the cylinder ports 1^e, 1^f. The main valve is fixed on a hollow or tubular stem, 14^c, which passes through a stuffing box, 10^c, in the lower head of the valve chest. The piston heads being subject to exhaust pressure on their outer sides, and to steam pressure, in opposite directions, respectively, on their inner sides, it will be seen that the main valve is in perfect balance, as to pressure and its weight, which is comparatively slight and acts downwardly, may, if desired, be compensated by any suitable known form of counterbalance in the ordinary manner.

The cut off valve comprises two sleeves or annular heads, 15, each connected by ribs to a central hub, and fitted truly to reciprocate in one of the piston heads of the main valve. The heads of the cut off valve are secured at a determined and invariable distance apart, upon a stem, 15^b, which extends downwardly, through the tubular stem, 14^c, of the main valve.

The main steam distribution valve may be actuated by any suitable known valve operating gear having the capacity of effecting reversal of the direction of rotation of the crank shaft, and of imparting maximum travel to the valve, when adjusted for either forward or back motion. The Stephenson link motion, which is, by reason of its simplicity and ready applicability, well adapted for operating the main valve, has therefore been selected for exemplification herein, and as shown, comprises, as usual, a slotted reversing link, 16, which is coupled, near one of its ends, to the rod, 17^a, of the forward eccentric, 17, and, near the other end, to the rod, 18^a, of the backing eccentric, 18. The stem 14^c, of the main distribution valve, carries, on its lower end, a cross head, 14^d, which is fitted to slide on guides, 14^e, bolted to the adjacent member of the housings, 2. A die or block, 16^a, fitted in the slot of the reversing link, 16, is journaled on a pin, 14^f, projecting from the cross head.

A reverse lever, 19, which is journaled in a bearing, 19^a, on the housing member which carries the guides, 14^e, is coupled by a rod, 19^b, to the reversing link, and is inovable over a segment, 20, in which is formed an ahead notch, 20^a, and an astern notch, 20^b. By movement of the reverse lever into engagement with one or the other of said notches, the reversing link is moved into position to impart movement to the cross head, 14^d, and connected main distribution valve, from either the forward or the backing eccentric, as the case may be, the traverse of the valve being effected to the maximum due to the throw of said eccentric. No notches

for different points of cut off are provided in the segment, 20, as it is intended that the main valve shall have full travel for either forward or back motion of the engine.

5 Variable travel, to effect longer or short cut off, in forward motion, in which direction only the cut off valve is designed to be operated, as may from time to time be desired, is imparted to the cut off valve, 15, by a cut off link, 21, which is of the same type as the reversing link, 16, and has a die or block, 21^a, similarly fitted in its slot. The stem, 15^b, of the cut off valve, passes through a stuffing box, 14^c, on the lower side of the 10 cross head, 14^d, of the main valve stem, and is coupled, at its lower end, to the die 21^a. The cut off link is coupled, near one of its ends, to the rod, 22^a, of a cut off eccentric, 22, fixed on the crank shaft at an angle of 15 approximately ninety degrees to the crank (that of one hundred and eight degrees being one which is suitable), and its opposite end is pivoted to a bar, 23, fitted to slide, transversely to the common axis of the valve 20 stems, in guides, 23^a, bolted to the adjacent housing member. The specific means of pivoting the cut off link at one end which is herein illustrated, is not an essential of my invention, as that end, at which it is inoperative to impart movement to the cut off valve, may be otherwise pivotally supported, 25 in the discretion of a constructor skilled in the art.

A double armed cut off lever, 24, which is journaled in a bearing, 24^a, on the housing member adjacent to the bearing of the reverse lever, 19, so as to be operable by the engineer without changing his position in handling the engine, is coupled to the cut off 30 link by a rod, 24^b, and is movable over a segment, 25, in which is formed a plurality of notches, with any one of which the cut off lever may be engaged, by a latch handle, 24^c, and latch 24^d. By reason of the pivotal support of one end of the cut off link, its vibratory movements are derived wholly 35 from the cut off eccentric, 22, to which its opposite end is connected. When the cut off link is in the position in which its pivot to its guide bar is in line with the cut off valve stem, no movement will be imparted to the cut off valve, 15, and the main valve being moved through its full traverse, in either forward or back motion, as before 40 stated, steam distribution will be effected at full stroke. By outward movement of the cut off lever, and resultant inward movement of the cut off link, 21, a greater or less degree of traverse will be imparted by the 45 cut off eccentric, 22, to the cut off valve stem, 15^b, and connected cut off valve, 15, and steam will be cut off at a correspondingly shorter or longer period in the stroke of the piston.

50 85 In starting the engine ahead, the cut off

link is adjusted to the position in which its pivot to its guide bar is in line with the cut off valve stem, so as to be inoperative on the cut off valve, the throttle is opened, and the reverse lever is, as shown in Fig. 1, engaged 70 with the ahead notch of its segment. After getting under way, the cut off lever is moved to position on its segment to adjust the cut off link to the point of cut off desired, the adjustment being shown in Fig. 1 as for one 75 quarter stroke cut off. Before stopping or reversing, the cut off lever is always moved to position to render the cut off link inoperative on the cut off valve, and the engine is handled by the reverse lever, which effects 80 full stroke of the main valve, in either direction of movement of the crank shaft, and continuously throughout such movement, whether or not the cut off valve may be 85 operated.

Among the advantages of my invention which will be apparent to those familiar with the construction and operation of steam engines of the marine type, are the low first cost and maintenance charges of an engine 90 embodying the invention, as compared with a multiple expansion engine of equal power; the economical utilization of steam by the expansion mechanism provided; and the capacity of quick and easy handling of the 95 engine and reduced liability to stoppage on the center in the operation.

I claim as my invention and desire to secure by Letters Patent:

1. The combination, in a single cylinder 100 steam engine, of a cylinder; a piston fitted to reciprocate therein; a main distribution valve, comprising two connected pistons, each having a port adapted to register with a cylinder port; a cut off valve, comprising 105 two connected pistons, each adapted to control a port of one of the main valve pistons; a forward and a backing eccentric; a slotted main valve link, coupled to the rods of 110 said eccentrics; a die fitting the slot of said link and coupled to the stem of the main valve; a slotted cut off valve link; a support to which said link is pivoted at one end and which is movable transversely to the line of 115 valve traverse; a cut off eccentric; an eccentric rod coupled to said eccentric and to the end of the cut off valve link farther from its pivotal support; a reverse lever coupled to the main valve link; and a cut off valve lever, journaled adjacent to said reverse lever and coupled to the cut off link.

2. The combination, in a single cylinder 120 steam engine, of a cylinder; a piston fitted to reciprocate therein; a main distribution valve controlling the cylinder induction and 125 eduction ports; a cut off valve; a slotted main valve link, coupled to the rods of forward and backing eccentrics; a die fitting the slot of said link and coupled to the stem of the main valve; a slotted cut off link,

coupled, at one end, to an eccentric rod; a support, movable transversely to the line of valve traverse and coupled to the other end of said cut off link; a die fitting the slot of 5 said cut off link and coupled to the stem of the cut off valve; and manually operable levers, pivoted, adjacent one to the other,

and coupled, respectively, to the main and to the cut off link.

J. SNOWDEN BELL.
